UNITED STATES PATENT OFFICE.

FREDERICK S. BOSWORTH, OF PROVIDENCE, RHODE ISLAND, ASSIGNOR TO
THE WEYBOSSET MILLS, OF SAME PLACE.

DESIGN FOR CASSIMERES.

SPECIFICATION forming part of Design No. 13,004, dated June 27, 1882.

Application filed March 30, 1882. Term of patent 7 years.

To all whom it may concern:

Be it known that I, FREDERICK S. BOSWORTH, of the city and county of Providence, and State of Rhode Island, have invented a new and useful Design for Fancy Cassimeres; and I do hereby declare that the following specification, taken in connection with the accompanying drawing, forming a part of the same, is a full, clear, and exact description thereof.

The novel design, hereinafter described, consists in a broken diamond pattern composed of blocks of different sizes, and of a color other than that of the ground of the fabric, combined with broken lines of threads of a still different color, the whole producing a systematic mottled or cloud effect, which may be varied by broken lines of another color running both longitudinally and transversely of the fabric, and dividing the surface of the same into rectangles.

Referring to the drawing, *a a' a²* are blocks varying in size, the said blocks being arranged so as to produce a broken diamond pattern.

b b are broken lines of threads of a different color, which assist to give to the fabric a mottled or cloud effect.

In combination with the blocks *a a' a²*, and the broken lines *b b* of threads, there may also be arranged broken lines of threads *CC'*, which traverse the fabric in directions at right angles to each other, thereby dividing the mot-

tled or clouded surface of the fabric into rectangles.

The fabric may be woven in any preferred variety or combination of colors for giving a desirable effect to the design above described, the characteristic feature of which is a broken diamond pattern composed of blocks of different sizes, combined with broken lines of threads of another color, producing a systematic mottled or cloud effect, which may be varied by other broken lines crossing the surface of the fabric and dividing it into rectangles.

What I claim as my invention, and desire to secure by Letters Patent, is—

1. The design for fancy cassimeres, consisting of figures of a broken diamond shape composed of blocks of different sizes, combined with broken lines of threads of a different color arranged upon the ground of the fabric and producing a mottled or cloud effect, substantially as set forth.

2. The design for fancy cassimeres, consisting of figures of a broken diamond shape composed of blocks of different sizes, broken lines of threads combined with said blocks to produce a mottled or cloud effect, and broken lines traversing the surface of the fabric and dividing it into rectangles, substantially as set forth.

FREDERICK S. BOSWORTH.
